ABSTRACT OF THE DISCLOSURE

Disclosed herein is an apparatus for doffing and collecting bobbins from a spinning frame which includes a movable inclined plane having an edge that engages the lower edges of the bobbins so as to move each bobbin upwardly as the bobbin slides along the edge between a lower portion and an upper portion by that vertical motion required to disengage the bobbin from a spindle and which includes a bin simultaneously movable with and relative to the inclined plane. The motion of the bin relative to the inclined plane serves to distribute bobbins along the length of the bin even as the bin moves with the inclined plane along a spinning frame.

The present invention relates to a vehicle for doffing and collecting filled yarn bobbins from a spinning frame.

Spinning frames are conventionally used in spinning a plurality of rovings into a corresponding equal number of yarns, each frame usually being capable of simultaneous spinning of 100 or more yarns. As the yarns are spun they are wound on corresponding individual bobbins mounted along one of the sides of the frames. The bobbins provide convenient packages whereby the yarns may be easily transported and fed to subsequent operations such as the weaving of fabrics.

As the bobbins on a spinning frame become filled with yarn they must be removed or doffed from the frame and replaced by empty bobbins. Normally, a spinning frame is operated so that all of the bobbins on the frame at any one time become filled with yarn at the same time. As a result, complete removal and replacement of the yarn filled bobbins may be accomplished at one time rather than on a piece-meal basis.

Heretofore, it has been usual practice for the individual operating each spinning frame to remove the bobbins from the frame by hand. Due to the relatively large number of bobbins removed, the operator normally has a relatively large collecting bin mounted on wheels or casters into which the yarn-filled bobbins are randomly dropped as they are removed. As is apparent, the removal or doffing of the bobbins from the spinning frame in this manner is not only tedious and time consuming but the random dispersion of the bobbins in the bin creates problems in subsequent removal of the bobbins from the bin at the next operation.

By way of the present invention there is provided a bobbin doffing and collecting vehicle which will not only remove the yarn-filled bobbins from the spindles of the spinning frame but will also deposit the bobbins in a relatively orderly manner in a collection bin forming a part of the vehicle. As a result, the operator need only provide locomotion and guidance for movement of the vehicle along the row of bobbins to be doffed from the spinning frame. The invention provides advantages in that the removal of the yarn-filled bobbins from the spinning frame may be accomplished at a faster rate, more bobbins per unit volume of the collection bin may be collected due to the orderly deposition of the bobbins in

2

the bin, and the removal of the bobbins from the collection bin at a subsequent operation is more readily accomplished.

These and other advantages of the present invention will be more apparent from the following discussion and the accompanying drawings wherein:

FIG. 1 is a side elevational view illustrating the bobbin doffing and collecting vehicle of the present invention.

FIG. 2 is a top view of the bobbin doffing and collecting vehicle shown in FIG. 1.

FIG. 3 is a end view of the bobbin doffing and collecting vehicle as shown in FIG. 1.

FIG. 4 is a view in partial section of the manner in which the half gears used to impart reciprocating motion to the collection bin are integrally mounted on a common axis.

FIG. 5 illustrates an alternative manner in which the half gears may be mounted on the vehicle for providing a reciprocating motion to the collection bin.

Briefly described, the bobbin doffing and collecting vehicle of the present invention comprises a supporting platform mounted for movement on wheels or casters, a bobbin doffing or removing means secured to and extending upward of one side of the supporting platform, a collection bin movably mounted on the supporting platform for reciprocation with respect to the platform, and drive means connected between the wheels of the supporting platform and the collection bin whereby continued movement of the supporting platform in a single direction imparts a corresponding relative reciprocating motion to the collection bin.

Referring first to FIG. 1, a side view of the bobbin doffing and collecting vehicle is illustrated. There is provided a supporting platform 11 having a plurality of wheels 15 mounted on its underside. The wheels are preferably mounted in groups of three as best seen in FIG. 3, there being one group positioned at each of the end portions of the platform and a third group positioned approximately mid-way between the ends of the platform. The third group of wheels provides the driving force for reciprocating the collection bin of the vehicle as will be explained in further detail later in the description.

The wheels of each group are fixedly mounted on an axle or shaft 13 which is preferably journaled in a series of axle supports 14 conveniently spaced on the underside of the supporting platform. In this manner, both the wheels 15 and the corresponding axle 13 rotate in the axle supports 14 as the supporting platform is moved across a floor or other substrate.

The axle 13 of the group of wheels mounted mid-way of the supporting platform is of somewhat greater length than the other axles and extends outward from underneath and beyond one of the longitudinal edges of the supporting platform. A main driving gear 31 is fixedly secured to the end of this axle and serves to engage and drive two systems of gears which provide reciprocating motion to the collection bin.

It should be understood that the groups of wheels 15 mounted at either end of the supporting platform may have different mountings than that previously described. For example, rather than being fixed to the axle they may be bearing mounted and independently rotatable. Furthermore, they may be altogether independently mounted and may even be pivotal to allow for easier turning movement of the platform.

Also along one of the longitudinal edges of the supporting platform and fixedly secured thereto are two vertical supporting members 41 and 42. These supports are in spaced apart relationship on either side of the mid-point of the supporting platform. A horizontal sup-

port 43 extends between the upper ends of the vertical supports. On the upper side of the horizontal support is secured an angular extension member 44 which extends outward from the side of the vehicle as defined by the supporting platform and the various supports 41, 42 and 43. At the outer end of the extension member 44 is mounted an inclined plane 45 and a guide arm 47 both of which cooperate to doff the successive yarn-filled bobbins from the spindles of the spinning frame and direct them to the collection bin of the vehicle, all of which may best be understood by reference to FIGS. 1 and 2 wherein a plurality of yarn-filled bobbins are indicated by phantom lines in the manner in which they are positioned on the spinning frame with their lower edges in sequence along a substantially horizontal line of reference. As illustrated, the leading edge of the inclined plane 45 is positioned in such a manner as to pass along the line of reference and under the lower side edge of each bobbin as the supporting platform 11 is moved ahead adjacent the spindles and along a line of motion substantially parallel to the line of reference. Further movement of the plane 45 imparts sufficient vertical motion to a bobbin as the bobbin slides along a length of the plane 45 between a lower portion and an upper portion to cause the bobbin to slide up and off the top of the spindle on the spinning frame. While this movement is taking place the guide arm 47, which is mounted on the rear of the inclined plane, engages the side of the bobbin and directs it toward the collecting bin. A trough 46, affixed to the inclined plane, completes the bobbin doffing means. The trough serves to direct the doffed bobbins into the collection bin.

As is apparent the extension member 44 must be of sufficient length to place the bobbin doffing means in a position to engage the undersides of the individual bobbins as the vehicle of the present invention passes alongside of the spinning frame.

A collection bin 20 is positioned for independent longitudinal movement on the upper surface of the supporting platform 11. The bin comprises a generally rectangular box having a width which is preferably substantially the same as the length of the individual bobbins although wider dimensions may be employed. The volume of the bin should be at least sufficient to accommodate all of the bobbins which would be removed and collected at one time from the spinning frame.

On the underside of the bin 20, preferably near the corners thereof, a plurality of wheels or casters 21 are mounted by means of supports 22. The wheels 21 of the collection bin ride in corresponding longitudinal runways 16 formed into the upper surface of the supporting platform 11. In this manner, the collection bin 20 is guided throughout its reciprocatory movement.

Secured to an upper longitudinal edge of the collection bin is an elongated gear rack 23. Between the gear rack and the main driving gear 31, previously described, are two systems of gears which provide the collection bin with reciprocatory movement. One system periodically moves the collection bin in one direction relative to the supporting platform while the other system provides the opposite periodic movement.

The two systems of gears may best be described with reference to FIGS. 1 and 3. One system includes driving gear 31, intermediate gear 32, transfer gear 34 and half gear 36. The second system includes driving gear 31, supplementary driving gear 31', intermediate gear 33, transfer gear 35 and half gear 37. As is apparent, the systems include identical corresponding gears with the exception of the additional supplementary driving gear 31' included in the second system. The addition of this gear allows the corresponding half gears 36 and 37 to rotate in opposite directions. By positioning the teeth portions of the half gears 180° out-of-phase with respect to each other, best seen in FIG. 2, only one gear system will be in engagement with the gear rack at any one time. As a

result while half gear 36 of the first system engages the gear rack the collection bin 20 is propelled in one direction. This movement stops when the toothless portion of half gear 36 rotates into an adjacent position with the gear rack. However, at the same time that half gear 36 disengages the gear rack the teeth of the oppositely rotating half-gear 37 move into engagement with the gear rack thus propelling the collection bin 20 in an opposite direction with respect to the supporting platform than its previous movement caused by the first gear system.

The half gears 36 and 37 and gear rack 23 are preferably of such construction and dimensions that the collection bin may be reciprocated with sufficient amplitude to alternately position its opposite ends beneath the trough 46 of the bobbin doffing means.

The precise embodiment illustrated in FIGS. 1 and 3 provides that both gear systems be substantially superimposed on each other so that half gears 36 and 37 are rotatably mounted on the same axis. The specific manner 20 of the uni-axial mounting of half gears 36 and 37 and their corresponding transfer gears 34 and 35 is shown in FIG. 4. Gears 34 and 36 are fixedly mounted on the ends of shaft 38. Intermediate of the gears 34 and 36 is a concentric hub 39 independently rotatably mounted 25 on shaft 38. Secured to the opposite ends of the hub are gears 35 and 37.

Both gear systems are mounted on a fixed gear support 12, shown in FIG. 3, which is secured to the longitudinal edge of the supporting platform immediately above the 30 main driving gear 31.

An alternative embodiment of the present invention is shown in FIG. 5 which provides that both gear systems be substantially separated from each other. This is generally indicated by the spaced apart relationship of half 35 gears 36" and 37". Of course, this arrangement may necessitate an extended gear rack 23" in order that adequate amplitude of reciprocation be obtained for the collection bin.

Thus, having described the structure of the bobbin 40 doffing and collecting vehicle and the individual functions of its component parts the overall coordinated operational features of the present invention are pointed out to indicate the advantages obtained when the vehicle is placed in use.

The bobbins on a spinning frame are mounted on spindles in a long continuous row generally indicated by the phantom lines in FIGS. 1 and 2 and which places their lower edges in sequence along a substantially horizontal line of reference. When these bobbins become filled 50 with yarn and it is desired to remove or doff them from the frame the bobbin doffing and collecting vehicle of the present invention is placed at the head of the row by the operator. The vehicle is oriented so that the front of the inclined plane member faces down the row of yarn filled bobbins and is in line with their lower outer edges. Preferably, the collection bin on the vehicle is in a position at either extreme end of the collection bin will be located immediately beneath the trough 46 and a complete first layer of bobbins may then be deposited into the bin.

The operator begins the operation by pushing the vehicle along a line of motion adjacent the spindles and the row of bobbins whereupon a lower portion of the inclined plane member 45 engages the lower edges of the bobbins and motion of the lower edges along the plane member 45 between the lower portion and an upper portion lifts the bobbins off the spindles. This procedure is indicated in FIG. 1 wherein the bobbins are shown being raised by the inclined plane. As the bobbins are withdrawn from the spindles the guide arm 47 engages 65 the sides of the bobbins and tilts them toward the trough side of the inclined plane member. This is most easily understood by reference to FIG. 2. When the bobbins have completely disengaged their spindles they fall into the trough and are guided to the collection bin by the 70 guiding means provided by the guide arm 47 and trough 75

46. In the bobbin collecting means provided by the collection bin, the bobbins are deposited in a somewhat orderly arrangement in the bottom of the bin.

At the same time that the bobbins are being withdrawn from the spinning frame the movement of the supporting platform causes the interconnected series of gears to rotate and impart relative movement to the collection bin. The gears are so designed that the incremental movement of the supporting platform during the withdrawal of adjacent bobbins produces a corresponding incremental movement in the collecting bin which is approximately equal to the width of a bobbin. In this manner, it is possible to deposit the bobbins in side-by-side relationship during the movement of the supporting platform along the spinning frame. Upon reaching the end of a deposited row of bobbins, the relative movement of the collection bin is reversed by the interconnected series of gears. Continued movement of the supporting platform 11 produces continued relative movement in the collection bin to thereby deposit a second layer of bobbins over the first layer. Since the relative movement of the collection bin has been reversed, the second layer of bobbins is deposited in an opposite direction to which the first layer was deposited.

As the vehicle continues to move down the line of bobbins on a spinning frame the collection bin reciprocates relative to the supporting platform whereby successive layers of bobbins may be deposited with the bin. Any misalignment of the bobbins as they are deposited into the collection bin may be easily remedied by the operator as he moves the vehicle along the spinning frame.

Thus, having described the present invention it will be apparent to those skilled in the art that certain modifications and variations may be made without departing from the spirit and scope of the invention and therefore it is intended that the present invention be limited only as defined in the appended claims.

I claim:

1. In an apparatus for doffing a plurality of bobbins from spindles on which the bobbins are positioned so that their lower edges are in sequence along a substantially horizontal line of reference and so that a vertical motion of each bobbin relative to the line of reference causes the bobbin to be dis-engaged from a spindle; a platform movable along a line of motion substantially parallel to said line of reference and adjacent said plurality of bobbins; a bobbin removing means for removing bobbins from said plurality of spindles, said bobbin removing means having an inclined edge which is positioned to pass along said line of reference and to engage a lower edge of a bobbin with a lower portion when said platform is moved along said line of motion and which is of sufficient length between said lower portion and an upper portion to impart said vertical motion to a bobbin as said inclined edge passes along said line of reference; bobbin collecting means for collecting bobbins, said bobbin collecting means being positioned on and movable with said platform and being independently movable on and relative to said platform in response to motion of said platform along said line of motion; and bobbin guiding means for guiding a bobbin removed from a spindle by said bobbin removing means into said bobbin collecting means.

2. The apparatus of claim 1 including reciprocating

means for imparting a reciprocating motion to said bobbin collecting means in response to said motion of said platform along said line of motion.

3. The apparatus of claim 2 in which said bobbin guiding means comprises a guide bar positioned to deflect a bobbin toward said bobbin collecting means subsequent to said vertical motion and a trough positioned to support said bobbin between said bobbin removing means and said bobbin collecting means.

4. The apparatus of claim 2 in which the bobbin collecting means comprises a bin mounted on wheels and in which the upper surface of the platform is provided with grooves for guiding the movement of the wheels of the bin.

5. The apparatus of claim 4 in which the reciprocating means comprises a gear rack secured along one side of the bin, a first system of gears adapted to engage the gear rack and provide movement to the bin in a first direction relative to the platform, a second system of gears adapted to engage the gear rack and provide movement to the bin in a second direction opposite to said first direction, and means to drive both first and second gear systems.

6. The apparatus of claim 5 in which the means to drive both first and second gear systems comprises a single gear which simultaneously engages both said gear systems and is driven by at least one wheel upon which the platform is mounted.

7. The apparatus of claim 5 in which the means to drive both first and second gear systems comprises separate gears each of which is in turn driven by at least one wheel upon which the platform is mounted.

8. The apparatus of claim 5 in which the first and second gear systems both include half gears for engaging the gear rack on the bin, the half gear of the first gear system being 180° out-of-phase with the half gear of the second gear system.

9. The apparatus of claim 8 in which the bobbin guiding means is located substantially mid-way along the side of the platform and the first and second gear systems are substantially superimposed on each other and are also fixedly located approximately midway along the side of the platform.

10. The apparatus of claim 8 in which the bobbin guiding means is located substantially mid-way along the side of the platform and the first and second gear systems are substantially separated from each other and are fixedly located beneath but proximately on either side of the bobbin guiding means.
